US0D1040260S

(12) **United States Design Patent** (10) Patent No.: **US D1,040,260 S**
(45) Date of Patent: **** Aug. 27, 2024**

(54) **HANDLE FOR JUMP ROPE**

(71) Applicant: **VELITES FITNESS, S.L.**, Zizur Mayor (ES)

(72) Inventor: **Matías Hernández Van Waes**, Pamplona (ES)

(**) Term: **15 Years**

(21) Appl. No.: **35/513,307**

(22) Filed: **Jun. 29, 2021**

(80) **Hague Agreement Data**

Int. Filing Date: **Jun. 29, 2021**

Int. Reg. No.: **DM/215180**

Int. Reg. Date: **Jun. 29, 2021**

Int. Reg. Pub. Date: **Dec. 31, 2021**

(51) **LOC (14) Cl.** **21-02**

(52) **U.S. Cl.**

USPC **D21/672**

(58) **Field of Classification Search**

USPC D21/670, 672, 694, 567, 568; D08/303, D08/330, 360, 107; D23/250; D07/649, D07/650; D26/37-50; D22/118
